UNITED STATES PATENT OFFICE.

JOHN D. MARTIN, OF NEW STRAITSVILLE, OHIO.

FURNACE GRATE.

Application filed May 10, 1924. Serial No. 712,248.

To all whom it may concern:

Be it known that I, JOHN D. MARTIN, a citizen of the United States of America, and a resident of New Straitsville, Perry 5 County, State of Ohio, have invented certain new and useful Improvements in Furnace Grates, of which the following is a specification.

When burning coal which cokes considerably upon a grate with overlapping grate elements in a series of steps, the coal being delivered at the uppermost step, there is apt to be a coke formation at the uppermost steps which forms more or less of a persistent solid mass which will not work downward over the grate as it should while being consumed. This is particularly the case with a conical grate in which the coal is fed up through the center into the hottest 10 part of the furnace. Such a coke formation is objectionable for three reasons: First, it is difficult for the draft to find its way through it and burn it up thus making the grate as a whole less effective. Second, large fragments of coke break off from the 15 mass, roll down over the top of the fuel, reach the edge of the grate before they can be completely burnt, and pass into the ash so that there will be too much combustible 20 in the ash. Third, such pieces mix with the ash around the edge of the furnace wall, and being there, make the furnace wall and the ash so hot and in such a fused condition that they stick together, thereby resulting 25 in the formation of considerable clinker on the wall.

The object of this invention is, in a grate having overlapping grate elements in a series of steps, to provide means for intermittently lifting and separating the uppermost of the grate elements, and thereby agitating the fuel bed so as to prevent the formation of large coke masses. A further object is to provide a unitary operating mechanism 40 which will separate a number of the grate elements at the same time by lifting the uppermost grate element the greatest distance and the ones below by progressively lesser amounts. A further object is, in connection with a revolving conical grate, to provide an actuating mechanism for this agitation which is carried around with the grate and which is actuated by stationary elements with which the actuating mechanism comes in contact.

Such a grate to which this invention is

particularly adapted is shown in my application for furnace filed Nov. 12, 1923, Serial No. 674,176.

In the accompanying sheet of drawings 60 which forms a part of this specification—

Figure 1 is a plan of a conical grate which embodies this invention, the grate elements being broken away, and

Fig. 2 is a vertical section through the 65 grate.

A frame ring 10 through arms 11, 11 supports a vertical fuel-conveyor tube 12 in which a helical conveyor 13 is operated to lift and discharge fuel. An ash-ring 14 70 connects through arms 15, 15 with a hub 16 which turns on the fuel-conveyor tube above and supported from the ash-ring are overlapping grate-elements in the form of grate-rings of progressively diminishing 75 diameter and spaced apart so as to leave horizontal passages between them. These form a conical grate. A chain 17 revolves a sprocket wheel 18 on the fuel-conveyor tube, and this carries with it the ash-ring 80 and the conical grate.

Lifting elements consisting of vertical rods 19, 19 and triangular rocker pieces 20, 20 are carried by guides 21, 21 attached to the spokes of the sprocket wheel through 85 which the rods pass, and forks 22, 22 attached to the spokes of the sprocket wheel to which the triangular pieces are hinged. The triangular pieces are pinned to the lower ends of the vertical rods and as the 90 sprocket wheel revolves the triangular pieces intermittently engage the stationary arms of the frame-ring and the vertical rods are lifted. Each of these rods at its upper end has a series of contacting parts for engaging and lifting the grate-rings. The contacting parts are so disposed that the uppermost grate-ring will be first engaged and be lifted away from the one underneath. Then the second ring will be engaged and the two rings will rise together away from the third ring. Then the third ring will be engaged and lifted away from the fourth ring along with the previous rings. The 95 four lifting elements operate and lift at the same time and lift slowly but the triangular pieces drop off from the stationary arms and the lifting elements and grate-rings fall back quickly. It is not necessary to operate on all of the rings but only on those 100 near the top which support the fresh fuel. The fuel bed is thereby agitated and coking 105 110

into a large mass, both by the raising up and separation of the grate-rings and by their sudden drop back into place, is prevented.

5 I claim—

1. In a furnace, a conical grate consisting of a series of superimposed rings, means for revolving the grate, lifting elements carried with the revolving grate for separating 10 the rings, and stationary elements which are engaged by the lifting elements.

2. In a furnace, a conical grate consisting of a series of superimposed rings, means for revolving the grate, lifting elements carried with the revolving grate each of which has 15 a series of contacting parts for engaging and lifting the rings by progressively increasing amounts toward the uppermost, and stationary elements which are engaged by the lifting elements.

JOHN D. MARTIN
